(57) **CLAIM**

The ornamental design for a vented susceptor, as shown and described.

DESCRIPTION

FIG. 1 is a front perspective view of a vented susceptor showing our design;

FIG. 2 is a back perspective view thereof;

FIG. 3 is a left side view thereof; and,

FIG. 4 is a right side perspective view thereof.

The even dashed circular ring that crosses the triangular panels in FIG. 1 is unclaimed, but the surrounding surface area shown in solid lines is part of the claimed design. All other even dashed broken lines in FIGS. 1-4 form no part of the claimed design.
